UNITED STATES PATENT OFFICE

SIDNEY S. HOLLAND, OF KANSAS CITY, MISSOURI, ASSIGNOR OF ONE-HALF TO OSCAR RIEGER, OF KANSAS CITY, MISSOURI

WRINGER ROLL

Application filed May 29, 1930. Serial No. 456,928.

My invention relates to rollers and more particularly to resilient rolls arranged in parallel contacting relation in a wringer for rotation to extract water from clothes passed

5 through the wringer.

In devices of this character one of the rolls is ordinarily connected with driving means and effects rotation of the opposite roll through cogs, by reason of surface contact

10 of the rolls, or through engagement effected by the presence of clothes between the rolls. The rotation of the driven roll is assured

when a piece of cloth is held between the rolls, but when the rolls are wet with hot 15 soapy water, the surface of the driving roll slides over the surface of the driven roll, rendering the wringer rolls useless.

When the edge of a garment is applied to the recess formed by the meeting peripheries

20 of the rolls, when the rolls are wet with hot soapy water, the surface of the lower roll will slide on the garment and the upper roll, failing to rotate the upper roll because of slippage of the lower roll thereon, failing to 25 draw the garment into the wringer. Troublesome manipulation is therefore required to introduce the garment between the rolls to establish the frictional relation necessary for effecting the wringing, and the edge of

30 the garment cannot be manually pressed between the rolls due to the pressure of the upper roll in power machines of this character. In order to restore the utility of the rolls, and enable the lower roll to rotate the upper 35 roll, the rolls must be allowed to cool, or cold clear water must be thrown on the rolls.

The principal objects of my invention therefore are to assure frictional driving relation between driving and driven rolls, to 40 provide a frictional element on a relatively smooth wringer for effecting driving relation between a pair of rolls, to embody cooperating friction elements in a plurality of rolls, and to provide a driving element in a smooth 45 resilient roll without reducing the efficiency of the roll or interfering with its normal operation, whereby rotation of one roll by another may be assured under all normal operating conditions.

50 In accomplishing these and other objects

of my invention, I have provided improved details of structure, the preferred forms of which are illustrated in the accompanying drawing, wherein:

Fig. 1 is a perspective view of a clothes 55 wringer and portions of a support, including rolls constructed in accordance with my invention, part of a shield being broken away to better illustrate my invention.

Fig. 2 is an enlarged partly sectional view 60 of one end of a roll provided with a fabric inlay.

Fig. 3 is an enlarged fragmentary section 65 of a portion of a roll containing the inlay.

Referring in detail to the drawing:

1 designates generally a wringer frame, 2 a shaft rotatably supported by the wringer frame and connected in driven relation with actuating mechanism including a motor, not shown, and represented by the casing 3.

The shaft comprises the supporting element of a roll 4, and a second roll 5 including a shaft 6 is rotatably supported by the frame above and parallel with the first roll and held resiliently in engagement therewith by suitable means such as springs, not shown. Each roll includes a relatively hard core portion 7 and a relatively soft and compressible resilient cylindrical facing element 8 having a smooth surface.

The elements just described are in general those ordinarily found in wringers mounted at the edge of a tub, and clothes washed in soapy water in the tub are delivered to the pair of rolls to be grasped by the oppositely 85 rotating surfaces and drawn therethrough for extracting water from the clothes.

When the rolls are dry or are wet with cold water, the lower roll will engage the upper roll with sufficient friction to rotate 90 the same.

The presence of a piece of cloth between the rolls also provides necessary friction for enabling the lower roll to effect rotation of the upper roll.

When a cloth or similar object is not present between the rolls, and hot soapy clothes are being fed to the wringer, the surface of the lower roll will slide over the upper roll without effecting rotation of the upper roll.

My invention pertains particularly to means for assuring rotation of the upper roll by the lower roll, to draw clothes into the wringer, even when the rolls are wet with hot soapy water, including a strip 9 having a high coefficient of friction applied to the surface of one of the rolls and adapted to engage the opposite roll with sufficient adhering ability to assure rotation of the upper roll when the lower roll is rotated by the actuating mechanism of the machine.

I preferably inlay a strip including fabric in one of the rolls and provide a relatively shallow groove 10 in the roll to receive the strip, whereby the outer surface of the strip may lie in registry with the surface of the roll. The strip extends circumferentially of the roll entirely around the same, and is preferably located adjacent one end of the roll. I further preferably install strips in the same positions on both of the rolls, so that the surfaces of the inlaid strips will engage and form continuously operating and continuously engaged frictional surfaces on the rolls.

The strips consist preferably of resilient bodies including layers of cloth or gauze 11 imbedded in the bodies, whereby the threads of the gauze may lie on the surfaces of the strips and as the strips wear, other threads will be exposed to provide the frictional surfaces.

In using a wringer having rolls constructed in accordance with my invention, for example two rolls having circumferential frictional strips adjacent similar ends as in Fig. 1, the upper roll will be constantly rotated by the roll which is driven by the actuating mechanism of the machine. When the edge of a garment is held against the oppositely rotating surfaces of the rolls it will be drawn therebetween and the wringer will extract the water therefrom.

However much the rolls may be lubricated by hot soapy water the driving relation will not be affected and the wringer will always therefore operate without requiring special means or operations such as throwing cold water on the rolls for setting up rotation of the upper roll and effecting engagement of a garment by the rolls.

Portions of the garments operated on by the wringer may pass between the inserted strips without damage to the garment or interference with the operation of the rolls, since the portions of the rolls which support the relatively thin resilient strips will yield to substantially the same extent as the portions not provided with strips.

Attention is further called to the fact that improved rolls provided with the elements described to assure driving relation between the rolls will not readily break or tear and have surfaces that may easily be cleaned and

ter and clothes. Sanitary qualities are thus preserved and enhanced, as particularly desirable in a device of this character used in connection with clothes cleansing operations.

What I claim and desire to secure by Letters Patent is:

1. A wringer roll including a yielding cylindrical core, a facing for the core having a greater degree of resiliency than the core, and a plurality of layers of fabric embedded in and covering the facing at one end of the roll, and having a greater coefficient of friction than the exposed surface of the facing. 75

2. A wringer roll including a yielding cylindrical core, a facing for the core having a greater degree of resiliency than the core, and a fabric ring inlaid in and covering a portion of the facing, and having a greater coefficient of friction than the exposed surface of the facing. 80

3. A wringer roll formed of resilient yielding material and a plurality of threaded fabric layers inset in and covering a portion of the roll to provide a continual frictional driving surface for the roll so that as the strips wear, the threads on the inner strips will be exposed to provide additional frictional surfaces. 85

4. In a wringer roll having a yielding resilient periphery, a cylindrical fabric inset ring fixed to a portion of the resilient roll, and having a greater coefficient of friction than the surface of the roll to provide a driving surface for the roll. 95

5. In a wringer, a pair of contacting rolls having yielding resilient peripheries, and a cylindrical inset ring surrounding adjacent portions of each roll and having greater coefficient of friction than the surface of the rolls when the rolls are wet with soapy water 105 to effect driving relation between the rolls. 110

In testimony whereof I affix my signature.

SIDNEY S. HOLLAND.
